REFRIGERATOR CABINET

Edward W. Bottum, Detroit, Mich.

Application September 9, 1935, Serial No. 39,775

5 Claims. (Cl. 312—186)

The present invention relates to cabinets for refrigerators and more particularly to a novel accessory therefor which functions as a closure element, auxiliary to the main door, and has a shelf for the reception of articles being transferred to and from the food compartment when the door is opened.

It is well known that when the door which provides access to the food compartment of a conventional mechanical refrigerator is opened the cold air therein is very rapidly displaced by warmer air from the exterior of the refrigerator cabinet, due to the fact that the entire food compartment is open to the atmosphere when access to only a part of the food compartment is desired. The present invention has as its primary object to provide a mechanical refrigerator cabinet with a closure element for the food compartment, auxiliary to the main door, which permits access to a particular part of the refrigerator cabinet food compartment while it closes off the remainder of the compartment to prevent warm air from entering the same or the cold air therein from circulating outwardly of the compartment. More particularly the present closure element is used to close the lower part of the refrigerator food compartment so that when the main door is open the relatively heavy cold air will be trapped in the cabinet and prevented from circulating outwardly of the lower part of the food compartment to be replaced by warm air from the exterior of the cabinet. It thus becomes possible to remove ice cubes, bottles, etc. from the upper part of the food compartment with a much smaller thermal loss than ordinarily is the case with the result that the operation of the refrigerator becomes more economical and its food preserving efficiency is increased.

Another object of the present invention is to provide a closure for the lower part of a mechanical refrigerator food compartment which normally prevents circulation of air inwardly and outwardly thereof when the door providing access thereto is open and which may be moved to facilitate access to the entire food compartment, the said closure element when moved being adapted to function as a shelf for the reception of articles to be transferred to or from the food compartment. In providing a convenient resting place for articles it becomes possible for the articles to be transferred into or out of a refrigerator food compartment with great facility and the time period which the door and auxiliary closure element must remain open is materially

reduced with the result that a marked increase in efficiency is realized.

Still another object of the present invention is to provide means for mounting the combined closure element and shelf in a refrigerator cabinet so as to adapt it for use as an accessory on refrigerators already in use, or as standard equipment on refrigerators being manufactured. In its preferred form this means comprises brackets for pivotally supporting the closure element so that it may pivot with respect to the cabinet and move from a position where it traps air in the food compartment and to a position where it may function as a shelf. When the combined closure and shelf is functioning as a closure element it will be understood that it functions independently of the main door which is ordinarily provided on a refrigerator cabinet and when it is functioning as a shelf it provides a resting place for articles which is auxiliary to the shelves which are ordinarily found in a refrigerator cabinet.

With the above and other ends in view the invention consists in matters hereinafter more particularly pointed out with reference to the accompanying drawing in which

Figs. 1 and 2 are vertical cross sections illustrating different stages in the operation of the invention;

Fig. 3 is a section taken on the line 3—3 of 30 Fig. 1;

Fig. 4 is a fragmentary view illustrating a detail;

Figs. 5 and 6 are fragmentary cross sections illustrating a modified form of the invention; 35

Fig. 7 is a view taken on the line 7—7 of Fig. 5;

Figs. 8 and 9 are elevations of another form of device for supporting the combined shelf and closure element, and

Fig. 10 is a cross section illustrating still another form. 40

Like characters of reference are employed throughout to designate corresponding parts.

In the drawing there is illustrated a refrigerator cabinet 1 provided with a food compartment 2 to which access may be had by opening the door 3 which is hingedly supported with respect to the refrigerator cabinet in the usual manner. In the upper portion of the refrigerator cabinet food compartment is provided a mechanical refrigerating unit 4 and shelves 5 are mounted in the cabinet in the usual manner. Attached to the lowermost shelf 5 is a bracket 6, the bracket having a pair of diverging arms 7 with plates 8 at their upper ends adapted to engage 50

the lower surface of the shelf and being secured to said shelf by bolts 9 passing through plates 10 which engage the upper surface of the shelf. In order to permit air to circulate freely through a 5 refrigerator cabinet the shelves such as are shown at 5 are ordinarily formed of a wire grill and it will be seen that the plates 8 and 10 with the bolts 9 uniting the same provide a simple means for attaching the brackets 6 to conventional re- 10 frigerator shelves for the reason that the plates extend over two or more of the shelf grill members and the bolts 9 pass between the said grill members.

The numeral 11 indicates a combined closure 15 element and shelf having ears 12 receiving a pivot pin 13 which extends into the bracket 6. It will be understood that two of such ears 12 are provided on opposite sides of the combined closure element and shelf and that two brackets 6 20 are also provided, there being a bracket 6 located adjacent to each side wall of the refrigerator cabinet so as to support the shelf at two 1 widely spaced apart points. It will also be understood that the shelf 11 extends entirely across 25 the food compartment 2 and that its side walls are provided with wiping seals such as are designated by the numeral 14 and illustrated on the end of the element 11 for wiping engagement with the bottom wall 15 of the food compartment. 30 In other words the seal 14 is adapted to be duplicated on the sides of the elements 11 as well as on the end of the element as illustrated.

From the foregoing it becomes apparent that the combined closure element and shelf 11 is supported with respect to the lowermost refrigerator shelf 5 so that it may pivot with respect thereto. When it is in the position shown in Fig. 1 the door 3 may be opened and access may be had to the upper shelf 2 and to the usual ice 35 cube compartment in the apparatus indicated at 4 without the cold air in the lower part of the food compartment escaping through the open door. However, when access is desired to the other shelves 5 and to food resting upon the lower wall 15 the combined closure element and shelf may be moved from the position shown in Fig. 1 to a position where it projects outwardly of the food compartment. In order to facilitate use of the closure element 11 as a shelf the invention provides a link 16 which is pivotally connected at 17 to the shelf and which has a pin 18 40 on its other end extending into a slot 19 in the arm 7 of its respective bracket 6. This construction is duplicated at each bracket and when the 45 pin 18 is at the end of its respective slot 19 as illustrated in Fig. 2 the link 16 functions to hold the closure element 11 in a horizontal or substantially horizontal position whereby it functions as a shelf for the reception of articles to be 50 transferred into or out of the refrigerator food compartment.

It will thus be seen that it is possible through use of the present invention to have access to the upper part of a refrigerator food compartment 65 without the cold air circulating outwardly of the lower part of the food compartment and that the means which makes this possible functions as a shelf to facilitate quick transfer of articles to and from the refrigerator when access to the entire food compartment is desired.

In Fig. 4 the numeral 11a designates a combined shelf and closure element which is adapted to be supported in the manner described above between a pair of spaced apart brackets 6a, one 75 of which is illustrated in Fig. 4. A rod 13a ex-

tends between the pair of brackets 6a and through a tubular part 12a integral with the element 11a. In order to frictionally resist movement of the element 11a with respect to its pivotal support 13a the invention provides a pair 5 of washers 20 and 21 and a coiled spring 22 interposed therebetween so as to press the washer 20 into engagement with the bracket 6a and the washer 21 into engagement with the end of the tubular element 12a. The washers are thus 10 yieldably pressed into engagement with their corresponding parts so as to frictionally resist pivotal movement of the element 11a. It is preferred that means for offering a slight frictional 15 resistance to movement be provided in combination with the combined closure element and shelf so as to hold it in its vertical position as illustrated at 11 in Fig. 1.

Referring to Figs. 5, 6, and 7, the numeral 5a designates a refrigerator shelf and 23 looped 20 wire guides attached to the bottom thereof. The guides 23 preferably are formed of a single piece of wire bent to provide an elongated slot 24 and having the ends thereof welded together. Two 25 of such guiding means are provided and the two 25 are united by transversely extending strap members 25 which are secured to the bottom of the shelf through means of bolts 26 and plates 27 which rest upon the top of the shelf. The strap members 25 are preferably welded to the elements 23 so as to maintain them in rigid spaced apart relation. The two guide members 23 are united at their front ends by a cross rod 28 and a combined shelf and closure element 29 has studs 30 extending into the guide slots 24 so 35 that the shelf and closure element 29 may be moved to a position such as shown in Fig. 5 wherein one end of the shelf is supported by the studs 30 and guide elements 23 while the other end is supported by the transverse rod 28. When 40 the shelf and closure element is in the position shown in Fig. 5 it is adapted for service as a shelf and it will be observed upon reference to Fig. 6, when the shelf 29 is moved outwardly it passes beyond the supporting rod 28 and moves 45 pivotally into a vertical position where it functions as a closure element to permit the cabinet door being opened without the cold air in the bottom of the refrigerator food compartment circulating outwardly thereof.

In Figs. 8 and 9 there is illustrated a modified form of support for a combined shelf and closure element 31. In this form the element 31 is attached pivotally to a pair of plates 32, one of which is shown. The plates 32 are united with a shelf 33 of grill formation by means of bolts 34 and plates 35 which extend over several of the grill members forming the shelf 33. Certain of the bolts 34 are also employed to secure a bracket 36 beneath the plate 32, which bracket is provided with a slot 37 through which the end of a notched link 38 extends. The end of the link 38 is pivotally attached to a bracket 39 secured to the element 31. It will be seen upon comparison of Fig. 8 with Fig. 9 that the element 31 55 may be held in a horizontal position by the notched link 38 or that the notched link 38 may be moved to permit the element 31 to pivot to a vertical position in which it functions as means for trapping cold air in a refrigerator food compartment.

In Fig. 10 the numeral 39 designates a fragment of a refrigerator wall adjacent to a door opening having a sealing member 40. Hingedly connected to the wall 39 is a combined shelf 75

- and closure element 41 having a bumper 42 secured to one face thereof and adapted to engage the sealing element 40 to hold the element 41 in a horizontal position for service as a shelf. 5
5 The element 41 may be moved on its hinged mounting to a vertical position where it functions to prevent circulation of air outwardly of a refrigerator food compartment.

Although specific embodiments have been illustrated and described it will be noted that various changes may be made in the details of construction without departing from the spirit of the invention as defined by the scope of the appended claims, and such changes are contemplated.

15 What I claim is:—

1. Means for mounting a supplemental shelf and closure element on a grill type shelf of a refrigerator whereby it may be swung to alternative positions where it projects through the door opening of the refrigerator or where it acts 20 as a partial closure for said door opening, said means comprising a pair of brackets, each bracket having plates adapted to span a plurality of shelf grill members on opposite sides thereof 25 respectively, securing elements adapted to extend between the grill members to unite said pair of plates, and a supplemental shelf and closure element pivotally mounted in said pair of brackets.
2. Means for mounting a supplemental shelf and closure element on a grill type shelf of a refrigerator whereby it may be swung to alternative positions where it projects through the door opening of the refrigerator or where it acts as a 30 partial closure for said door opening, said means comprising a pair of brackets, each bracket having plates adapted to span a plurality of shelf grill members on opposite sides thereof respectively, securing elements adapted to extend between the grill members to unite said pair of plates, a rod extending between the pair of brackets and supported thereby, and a supplemental shelf and closure element having a tubular bearing portion received on said rod.
3. Means for mounting a supplemental shelf and closure element on a grill type shelf of a refrigerator whereby it may be swung to alternative positions where it projects through the door opening of the refrigerator or where it acts

as a partial closure for said door opening, said means comprising a pair of brackets, each bracket having plates adapted to span a plurality of shelf grill members on opposite sides thereof respectively, securing elements adapted 5 to extend between the grill members to unite said pair of plates, said brackets having elongate slots therein, a supplemental shelf and closure element, pintles on said supplemental shelf slidably received in said slots and supporting one end of 10 said supplemental shelf, and a transverse member uniting said brackets and providing a support for the other end of said shelf.

4. Means for mounting a supplemental shelf and closure element on a grill type shelf of a 15 refrigerator whereby it may be swung to alternative positions where it projects through the door opening of the refrigerator or where it acts as a partial closure for said door opening, said means comprising a pair of brackets, each 20 bracket having plates adapted to span a plurality of shelf grill members on opposite sides thereof respectively, securing elements adapted to extend between the grill members to unite said pair of plates, a supplemental shelf and closure, 25 pivots supporting said supplemental shelf and closure in said brackets, and friction means mounted on at least one of said pivots for yieldably opposing swinging movement of said supplemental shelf. 30

5. Means for mounting a supplemental shelf and closure element on a grill type shelf of a refrigerator whereby it may be swung to alternative positions where it projects through the door opening of the refrigerator or where it acts 35 as a partial closure for said door opening, said means comprising a pair of brackets, each bracket comprising a pair of upwardly diverging arms, a supplemental shelf pivotally mounted at the juncture of said arms, a slot in one of said 40 arms, a link connected to said supplemental shelf and having means riding in said slot, each arm having plates adapted to span spaced grill members of a shelf on opposite sides thereof respectively, and securing elements adapted to extend 45 between the grill members to unite the plates on opposite sides of the grill members.

EDWARD W. BOTTUM.
